TEKKOSH, OF OSAKA, JAPAN, A CORPORATION OF JAPAN, DOCK YARD.

PISTON.

1,371,108.

Specification of Letters Patent.

Patented Mar. 8, 1921.

Application filed June 27, 1917. Serial No. 177,382.

To all whom it may concern:

Be it known that I, SHINTARO OTSU, citizen of Japan, residing at No. 52 Honden 2 chome, Nishi-ku, Osaka, Japan, have invented certain new and useful Improvements in Pistons; and I do hereby declare the following to be a full, clear, and exact description of the invention, such as will enable others skilled in the act to which it 10 appertains to make and use the same.

This invention relates to a piston, in which a square, circular or wedge-shaped hole decreasing its sectional area gradually toward the outer edge is made between the 15 edges of a packing ring which is fitted into a groove on the circumferential face of the piston, and a wedge-shaped piece of corresponding shape, being pressed out from its back by means of a helical spring or the 20 like, is secured into the hole.

The invention has for its object not only to press out a packing ring to a cylinder-wall but to distribute pressure in every direction and thus to absolutely prevent the leakage of 25 steam in order to increase efficiency and durability.

In the accompanying drawings: Figure 1 shows a sectional elevation of an example of a piston relating to the invention; Fig. 2 is a plan of the same omitting some parts; Fig. 3 is a side view showing the section of 30 part of a packing ring; Fig. 4 is a plan of a part; Figs. 5 to 7 are side views, showing some parts of the piston; Fig. 8 is a fragmentary sectional elevation showing one of the adjusting plates in position. Similar letters refer to similar parts throughout the several views.

(a) is a packing ring, which is applied 40 into a groove (d) formed between the piston-body (b) and a junk ring (c), and it may be separated into two or more segments along its circumference and also into two parts, up and down or axially, and the contacting edges (e) and (f) overlap each other 45 or are so made as to prevent leakage by some proper method.

At a certain position between the contacting edges (e) and (f), a wedge-shaped hole 50 (g) of square, circular or some other form of section is made, into which a wedge (h) of corresponding shape is fitted. (i) is a helical spring, put in a recess (j) made in the piston body, keeping its position by 55 means of a holder (k), which presses the

wedge (h) toward the cylinder wall. (m) is a stopper fixed to the piston body (b), and its projection (m') is fitted into a groove (n) which is made on the inner face of the packing ring (a), thus it prevents 60 the packing ring from turning around the piston body and also from changing relative position of the wedge (h) and the spring (i).

(c) is a junk ring which serves to hold 65 the packing ring at its proper position; (o), a ring conveniently made to adjust the position of the packing ring (a) by somewhat pressing it before fixing the junk ring (c); (p) is a packing material of soft metal applied to a recess between the wedge (h) 70 and packing ring (a), in order to relieve the wear of their contacting surface.

With the piston of the invention, tightness between the cylinder wall and the packing ring (a), or that of between the both contacting edges (f) of the packing ring (a), or that between the packing rings (a) and the side walls of the groove (d), is perfectly maintained, since the packing ring 80 (a) gives pressure in every direction by the action of wedge (h) which is placed between every two segments of the packing ring (a), and which is pressed by the spring (i) from its back. As the leakage of steam 85 in every part is thus prevented absolutely, the work of the piston is most effectual.

In almost all the packing rings in pistons which are already known, pressure acts only 90 radially, the tightness of their contacting edges and that of the space between the two sides of the rings and the side wall of the grooves being impossible to be kept perfect. So, when steam begins to leak it can not be repaired and the rings are to be replaced 95 anew. But in this invention, the wedge (h) being made to be pressed up as the circumferential face of the packing rings and their contacting edges wear themselves off, tightness is always kept uniform and in consequence the piston works most effectually. 100

If the spring which presses the wedge has become non-effective by being elongated beyond its elastic limit or by some other causes, its usefulness can easily be restored by applying a thin plate (r) between the spring (i) and body of the piston through a peep hole (o') bored in the ring (o) after taking off the cover (c).

On the whole, the principle of the inven- 110

tion lies in the fact that the segments of a packing ring are subjected to pressure radially toward the cylinder wall and also circumferentially, by means of a wedge (*h*) 5 applied into a proper bore with decreasing section toward the outer circumference of the packing ring made between the contacting edges of each segment of the packing ring, and pressed internally by means of a 10 spring (*i*). Thus the tightness of the other parts of the piston and that of the space between the cylinder wall and the packing ring, to which attention has not been duly paid hitherto, is kept perfect, and the results 15 are the increased efficiency of the piston and the saving of much trouble and cost of replacing of the various parts of the same in order to prevent steam leakage.

This invention can be modified as far as 20 it is compatible with the above-mentioned principle.

Having thus described my invention, what I claim is—

1. A piston packing comprising, in combination, a plurality of segments adjoining one another circumferentially and axially and having overlapping portions extending axially and circumferentially of the piston at the joints between said segments, registering recesses in said overlapping portions, and means in said registering recesses for exerting pressure against said segments circumferentially and axially of the piston.

2. A piston packing comprising, in combination, a plurality of segments having overlapping end portions provided with registering recesses at the joints therebetween, and means in said recesses for exerting pressure against said segments circumferentially and axially of the piston.

3. A packing ring comprising, in combination, a plurality of segments having overlapping parts provided with registering recesses at the joints therebetween so shaped 45 as to form outwardly tapering holes, wedges fitting in said holes and adapted to exert pressure against said segments in radial, circumferential and axial directions, and

means pressing said wedges radially outwardly in said holes.

4. A piston comprising, in combination, a plurality of packing segments adjoining one another circumferentially and axially and having registering recesses at the joints therebetween so shaped as to form outwardly tapering sockets, wedges fitting in said sockets and adapted to exert pressure radially, circumferentially and longitudinally of the piston, means pressing said wedges radially outwardly, and means limiting the 60 circumferential movement of said segments.

5. A piston comprising a body, a junk ring or clamping member, and a plurality of segments disposed between said body and ring and adjoining one another axially and 65 circumferentially, said segments having registering recesses at the joints therebetween so shaped as to form outwardly tapering holes, wedges fitting in said holes and adapted to exert pressure against said segments radially, circumferentially and axially 70 of the piston, resilient means bearing against said wedges, and devices adapted to be inserted between said resilient means and the piston body for increasing the tension of 75 said resilient means.

6. A piston comprising a body, a junk ring or clamping member, a plurality of segments disposed between said body and ring, devices for exerting pressure against said 80 segments, and a plate between said junk ring and said pressure exerting devices having openings therein through which said pressure exerting devices are accessible.

7. The combination with a plurality of 85 sectional packing rings having overlapping circumferential edges and overlapping ends provided with registering recesses, of means engaging in said recesses for exerting pressure radially and axially of said rings.

In testimony whereof I hereunto affix my signature.
